UNITED STATES PATENT OFFICE

157,700

SERVING TRAY

Rolland A. Price, Columbus, Ind., assignor to Co-lumbus Molded Plastics Corporation, Columbus, Ind., a corporation of Indiana

Application January 21, 1949, Serial No. 377

Term of patent 14 years

(Cl. D44—10)

To all whom it may concern:

Be it known that I, Rolland A. Price, a citizen of the United States, residing at Columbus, in the county of Bartholomew, State of Indiana, have invented a new, original, and ornamental Design for a Serving Tray, of which the following is a specification, reference being had to the accompanying drawing, forming a part thereof, wherein:

I claim:

The ornamental design for a serving tray, substantially as shown.

ROLLAND A. PRICE.
